(57) **CLAIM**

The ornamental design for a spine for a dusting implement, as shown and described.

DESCRIPTION

In use, the spine for a dusting implement is inserted into a cloth, paper or other material dusting implement.

FIG. 1 is a top plan view of my new design for a spine for a dusting implement; the bottom plan view is a mirror image of the top plan view;

FIG. 2 is a front elevational view of the spine for a dusting implement; the rear elevational view is a mirror image of the front elevational view;

FIG. 3 is a left side elevational view of the spine for the dusting implement; and,

FIG. 4 is a perspective view of the spine for a dusting implement.

The broken lines showing the handle are for illustrative purposes only and form no part of the claimed design.
